UNITED STATES PATENT OFFICE.

HARRY SOLOMON, OF NEW YORK, N. Y.

MACHINE FOR APPLYING BACKS TO MIRRORS.

Application filed June 17, 1924. Serial No. 720,671.

To all whom it may concern:

Be it known that I, HARRY SOLOMON, a citizen of the United States, and resident of New York city, in the county of New York and State of New York, have invented certain new and useful Improvements in Machines for Applying Backs to Mirrors, of which the following is a specification.

This invention relates to an improvement in a machine or mechanism which automatically applies backs to small mirrors, such as are carried in the pocket or in small handbags and the object of this invention is to produce a mechanism of this character which will apply backs made of paper, cloth, leather, or the like, to said mirrors, folding said backs about the marginal edges of the mirror and holding the same in position by means of a folded stiffening member which is applied to the mirror simultaneously with the application of the backing thereto.

A further object of this invention is to provide a mechanism which will apply a backing and a marginal edge-protecting portion to small mirrors of varying thicknesses without the possibility of breaking the mirror during such application.

Reference is to be had to the accompanying drawings, forming a part hereof in which

Figure 1 is a front elevation of the upper die member;

Fig. 2 is a front elevation of the central die member;

Fig. 3 is a front elevation of the lower die member;

Fig. 4 is an end view of the die shown in Fig. 3, parts being shown in section and broken away to disclose construction;

Fig. 5 is a plan view of the central die member disclosed in Fig. 2;

Fig. 6 is an end view of the upper die member disclosed in Fig. 1;

Fig. 7 is a vertical sectional view of the upper and lower die members showing the same in the act of bending or folding the mirror backing and the stiffening member preparatory to the application of the same to a mirror;

Fig. 8 is a perspective view of a portion of the central die member;

Fig. 9 is a sectional view of portions of the three die members co-operating to apply the backing to a mirror;

Fig. 10 is a plan view of the stiffening member which is applied to the back and side edges of a mirror;

Fig. 11 is a sectional view on the line 11-11 of Fig. 10;

Fig. 12 is a plan view of a finished mirror; and

Fig. 13 is a sectional view on the line 13-13 of Fig. 12.

Throughout the various views of the drawings, similar reference characters designate similar parts.

Referring to the article shown in Fig. 10: This constitutes a stiffening member 1 of thin malleable metal, which is provided with marginal edge portions 2 on all of its sides. This stiffening member 1 lies underneath and constitutes a reinforcement for the outer covering 3, which may be made of cloth, leather, paper or any ornamental fabric.

The machine hereinafter described acts to fold over the edges 2 on the dotted lines 5 of the stiffening member 1 and said folded-over edges 2 hold down similarly folded edge portions on the outer covering 3, so that the stiffening member is completely covered by the outer covering 3 and a backing and reinforced edge is provided completely around the mirror 4. The completed mirror is shown in detail in Figs. 12 and 13.

The mechanism for applying the backs to the mirrors is disclosed in detail in Figs. 1, 2, and 3 where it will be seen that the same is composed of three main parts, the same being an upper die portion 6 which co-operates with a lower die 7 to fold down the side edges 2 of the stiffening member 1 and backing 3 prior to the application of the same to the mirror. The third main portion of the machine comprises a central die portion 8 which co-operates with the portion 6 in the final application of the backing to the mirror.

Referring to the portion 6: At 9 is shown an upper plate which is provided with an

upwardly extending threaded stud 10 adapted to be received in a plunger 11, forming part of a press which vertically reciprocates the die 6. A set-screw 12 retains the die in its fixed position relative to the portion 11 of the plunger and prevents inadvertent rotation of the die while in use. The plate 9 is provided with a downwardly extending block 13 which has a flat under-surface 14. The block 13 is surrounded by an outer shell 15, the vertical movement of which with respect to the block 13 is limited by means of pins 16 projecting from the ends of the block 13 and entering slots 17 in the ends of the shell 15.

It will be seen therefore that the shell 15 may move vertically with respect to the block 13 within the limits of the slots 17.

At 18 are shown fingers which are pivoted at 19 in ears 20 which project laterally from the ends of the plate 6. These fingers are provided with slots 21 in their inner edges and said slots 21 are adapted to fit over a continuous wall 22 which extends about the face of the shell 15. Located above the pivots 19 for said fingers 18 are spring-pressed studs 23 which are forced outwardly under the impulse of springs 24. These studs 23 bear against the fingers 18 above their pivots 19, thus normally tending to cause the lower ends of said fingers to move inwardly so that the slots 21 embrace the wall 22 on the shell 15. It will be seen that when such engagement takes place, the shell 15 cannot move vertically and remains in fixed position relative to the block 13.

The lower die 7 is composed of a base 25 from which projects an upwardly extending block 26 surrounded by a frame 27. Said frame 27 is provided with a top portion 28 which projects outwardly and which is normally thrust upwardly by means of springs 29 located at each of its four corners. Studs 30 project upwardly from the base 25 within the springs 29 and serve to act as abutments for the top 28 of the frame 27 when said frame is pressed downwardly by the die 6 as will be hereinafter explained.

The ends of the frame 27 are provided with grooves 31 which form a passage for the fingers 18 on the die 6. The ends of the frame 27 are provided with slots 32 in which extend pins 33 which project from the ends of the block 26 and limit the upward movement of the frame 27 under the pressure of the springs 29.

In Fig. 7, the manner in which the dies 6 and 7 co-operate to bend down the side edges 2 of the stiffening member 1 and also the outer covering 3 is shown.

The stiffening member 1 which has its side edges slightly downwardly bent as disclosed at 34 in Figure 11, to aid in the bending movement as will be hereinafter ex-

plained, is placed upon the block 26 which is then in the position shown in Figs. 3 and 4. The covering 3 is placed on top of the stiffening member 1 and the die 6 is caused to descend. Said die 6 descends until its projecting edge 22 contacts with the top 28 on the frame 27 of the die 7. As the frame 15 is held in fixed position by means of the fingers 18 which are engaging with the edge 22, said frame 15 forces down the frame 27 against the tension of the springs 29 and as such movement continues, the block 26 forces the cover 3 and stiffening member 1 up into the frame 15 and against the under-face 14 of the block 13. (See Fig. 7).

The die 6 is then raised and as it is raised, the stiffening member 1 and cover 3 are retained within the frame 15 with their edges folded downwardly as shown in Fig. 7.

The central die 8 is then placed upon the die 7 for the application of the covering to the mirror. The die 8 comprises an outer frame 35 on which is supported a top 36. Said top 36 is secured to the frame 35 by means of screws 37 which pass through openings 38^a in the frame 35 and thread into said top 36. In order to compensate for mirrors of various thicknesses, resilient inserts 38 are located in recesses in the frame 35 and project upwardly from the frame 35 and space the top 36 from said frame 35. These inserts are made of any resilient material such as blocks of rubber, or if desired coil springs may be used. As the tops of these inserts 38 project above the upper face of the frame 35, they hold the top 36 at a distance therefrom so that a small space 39 lies between the under side of the top 36 and the upper face of the frame 35. The top 36 is provided with downwardly depending side flanges 40 and 41 which extend completely around the top 36 so that dust, dirt or shreds of material which accumulate during the operation of the mechanism cannot enter between the parts 35 and 36.

The top 36 is provided with an upper face 42 which is in the nature of a marginal edge strip extending completely around the top, and a depressed seat 43. The parts 42 and 43 are so shaped that they correspond to the under face of the frame 15 on the die 6, so that when said die descends down upon the die 8, the laterally projecting wall 22 on the frame 15 rests upon the marginal edge portion 42 of the top 36, and the under face of the downwardly projecting rim 44 on the frame 15 rests upon the seat 43 (see Fig. 9). At 45 is shown an inclined surface which extends completely around the central opening in the die, and which acts to bend inwardly the downwardly bent edges of the stiffening member 1. The face of said inclined surface 45 is curved or rounded, as disclosed in Figs. 8 and 9 so that it

tends to curl the edges of the stiffening member inwardly as will be hereinafter explained.

Located within the central opening in the die 8 is the mirror-elevating member 46 which is capable of being raised and lowered within the die, such raising and lowering movement, however, being restricted by means of pins 47 which extend inwardly from the ends of the frame 35 and enter into slots 48 located in the ends of the member 46. The member 46 is provided with a downwardly extending side wall 49 and a top piece 50 upon which the mirror is placed. The four edges of the top piece 50 are inclined or beveled as at 51, said beveled edge being curved or rounded to form a pressing surface which co-operates with the curved edge 45 on the top 36 to bend the edge of the stiffening member 1 and cover 3 inwardly and about the edges of the mirror.

On each of the ends of the top 36 is a cam 52 which is intended to contact with the fingers 18 and shift the same so that they are freed from their engagement with the wall 22 on the frame 15 and said frame can be forced upwardly as shown in Figure 9.

Assuming that the parts are in the position shown in Fig. 7. In this figure the stiffening member 1 and the fabric cover 3 have had their edges bent downwardly. The dies 6 and 7 are then separated, the upper die 6 ascending and carrying the bent stiffening member and cover within its frame 15 and against the flat under-face 14 of the block 13.

The die 8 is now placed upon the top portion 28 of the lower die 7, the under side of the frame 35 corresponding in shape to the upper face of the top 28 so that said die 8 rests securely upon the top 28. A mirror 4 is placed face downward upon the upper surface of the top piece 50 and the die 6 is then lowered. As the die 6 descends, the fingers 18 come into contact with the cams 52 on the top 36 so that said fingers are spread outwardly and are thus caused to become disengaged from the wall 22 on the frame 15. Thus, when the under side of said frame comes into contact with the upper face of the top 36 on the die 8, the frame is forced upwardly. As the die 6 continues its descent the frame 27 which surrounds the block 26 is forced downwardly against the tension of the springs 29. The bottom of the wall 49 on the mirror-elevating member 46 comes into contact with the upper face of the block 26 and rests thereon so that as the downward movement of the die 6 continues further, the mirror 4 is forced against the stiffening member and the edges of the stiffening member 1 and cover 3 are curled inwardly by the pressure of the inclined curved faces 45 and 51 on the top 36 and mirror-

elevating member 46 respectively. Figure 9 shows the parts in the act of beginning this "curling" or bending of the edges of the cover and stiffening member. It will be noted that the outer cover or backing is, in the completed structure, curled or tucked under the curled edge of the metal stiffening member, holding the edge of the fabric firmly in place and providing a smoothly drawn back covering and an even and smooth edge reinforcement for all of the edges of the mirror.

After the final pressure together of the dies has applied the backing, the die 6 is raised and the completed or backed mirror is removed.

I have shown the dies of such a form as is required for the backing of a mirror of substantially rectangular shape, but it will be obvious that any shaped mirror may be backed by a mere change in the shape of the dies.

It will also be seen that by the use of resilient spacers between the parts 35 and 36 I provide an arrangement whereby breakage of mirrors by reason of variances in thickness is avoided, for any excessive downward pressure upon the bending groove 45 by the block 13 as the die 6 is descending is taken up by the resilient spacers 38 before a pressure sufficient to break the mirror is imposed upon the mirror.

Having described my invention what I claim is:

1. A mechanism of the class described, comprising a pair of dies adapted to co-operate to partly fold the edges of a metal stiffener and a cover, a support for a mirror, said support having an exterior movable and resiliently supported frame provided with an inclined edge adapted to contact with and bend the folded edges of the stiffener and cover, and an inclined edge on the mirror support adapted to co-operate with the inclined edge on the exterior frame to completely fold the edges of the stiffener and cover over the edges of the mirror.

2. A mechanism of the class described, comprising an upper die, a lower die, and a die adapted to be placed between said upper and lower dies, said upper die and lower die adapted to co-operate to partly fold the edges of a cover for a mirror, said intermediate die being adapted to co-operate with the upper die to fold the bent edges of said cover over the edges of the mirror, parts of said intermediate die being spaced by resilient inserts.

3. A mechanism of the class described, comprising an upper die, a lower die, and an intermediate die, said upper die having a folding frame into which a stiffener and mirror cover are adapted to be forced by parts of the lower die to fold the edges of said stiffener and cover, said intermediate

die having a frame adapted to rest on top of the lower die, said frame having a top piece, resilient inserts extending between said frame and the top piece, a mirror-supporting member movable within said frame, and inclined edges on said mirror-supporting member and the top piece for co-operating with parts on the upper die to fold the edges of the stiffener and cover over the edges of a mirror held on the mirror-supporting member.

4. A machine of the class described comprising an upper die and a lower die, said upper die being adapted to hold a fabric cover and a metal stiffener for a mirror, said lower die having a mirror supporting member, a top piece surrounding said member, and inclined edges on the top piece and mirror supporting member for co-operating with the upper die for folding portions of the cover and stiffener held by the upper die over the edges of a mirror held upon the mirror supporting member.

5. A mechanism of the class described, comprising an upper die having a downwardly extending block, a frame surrounding the same and movable on said block, a lower die having an upwardly extending block and a spring-pressed frame surrounding said block, means for holding the frame on the upper die in fixed relationship to the block on said upper die so that said upper frame forces the frame on the lower die downwardly and the block on the lower die forces a cover for a mirror up into the upper frame when the two dies come together, an intermediate die having a mirror-supporting member, a top piece surrounding

said member, and curved inclined edges on said top piece and mirror-supporting member for co-operating with the block on the upper die for folding portions of the cover about the edges of a mirror held upon the mirror-supporting member. 40

6. A mechanism of the class described comprising a die for folding the edges of a cover and stiffening member about the edges of a mirror, said die having a supporting frame, a top member on said supporting frame, resilient inserts between said frame and top member, an inner member movable within said frame and within the top member, inclined edges on the top member, inclined edges on the inner member, means for pressing a mirror, cover and stiffening member down on the top member and on the inner member whereby the edges of said cover and stiffening member are folded over the edges of the mirror by the co-operating inclined edges on said top member and inner member. 50

7. A mechanism of the class described, comprising an upper die for holding a partly-folded stiffener and fabric covering, a lower die composed of an outer frame member, an inner member, and a supporting member; said supporting member resiliently supporting said outer member, and inclined edges on said inner member and outer member for co-operating to fold the stiffener and fabric covering over the edges of a mirror supported on the inner member. 60 65

Signed at New York city, in the county of New York, and State of New York, this 13th day of June, A. D. 1924.

HARRY SOLOMON.
